UNITED STATES PATENT OFFICE.

EDMUND A. SCHWARTING AND AUGUST R. SCHRADE, OF WACO, TEXAS.

POSTING DEVICE.

Application filed February 23, 1924. Serial No. 694,703.

To all whom it may concern:

Be it known that we, EDMUND A. SCHWARTING and AUGUST R. SCHRADE, citizens of the United States, residing at Waco, 5 in the county of McLennan and State of Texas, have invented certain new and useful Improvements in Posting Devices, of which the following is a specification, reference being had to the accompanying drawings.

This invention relates to transfer devices for use in connection with loose-leaf binders and has for its object the provision of a novel device for posting loose leaves in a 15 peculiarly constructed binder such as that which forms the subject matter of our co-pending application filed February 23, 1924, Serial No. 694,704, in which application we have disclosed a loose-leaf binder including 20 covers through which are passed posts which are slidable into inactive position and which are held in place by peculiar spring pressed but manually releasable latch means.

The specific object of this invention is to 25 provide a tray-like structure upon which such a loose-leaf binder may be laid and the posts released into inoperative position, a tray element or platform being provided on which may be laid the successive leaves or 30 groups of leaves removed from the released binder, together with new leaves which are to be added or inserted at any point, means being also provided for squaring up the pile 35 of leaves to bring the post receiving holes in registration.

Another object is the provision of a device 40 of this character which is adjustable for handling leaves of different sizes and which is, moreover, provided with auxiliary means for permitting or effecting the positioning of statement sheets or other leaves of different sizes from the ledger of leaves.

An additional object is the provision of a 45 device of this character which avoids the well-known operation of the usual post to post transfer.

A further object is the provision of a 50 structure of this character which will be simple and inexpensive in manufacture, easy to use, efficient and durable in service and a general improvement in the art.

With the above and other objects and advantages in view, the invention consists in 55 the details of construction and arrangement of parts to be hereinafter more fully de-

scribed and claimed, and illustrated in the accompanying drawings in which:—

Figure 1 is a perspective view of the device showing a binder thereon in initial position.

Figure 2 is a perspective view looking towards the rear of the device.

Figure 3 is a cross section on the line 3—3 of Figure 1.

Figure 4 is a horizontal section showing 65 the latch or catch mechanism of the binder.

Figure 5 is a sectional view through the upper tray member showing the binder top cover and a plurality of leaves thereon.

As stated above, the device is intended 70 for use in connection with a specially constructed binder which is disclosed in our co-pending application but which is also here illustrated as being essential to a proper understanding of the invention.

Referring more particularly to the drawings, we have shown the binder as including a base, a cover and post co-operating with latch means. The numeral 10 designates the base as a whole, which includes a 80 relatively stationary section 11 and a movable section 12. The hinged structure connecting these sections is not illustrated as it forms no part of the present device and for the further reason that it is well-known 85 in the art and might be varied within wide limits. This base is intended to support a plurality of superposed leaves or sheets 13 which, as is well-known, are formed with holes 14. At spaced points the stationary 90 section 11 of the base has plates 15 embedded or otherwise anchored therein, and slidably engaged through these plates are posts 16 which are provided at their lower ends with enlarged heads 17 preventing them 95 from being withdrawn upwardly out of association with the base. The plates 15 are countersunk or recessed for the reception of the heads 17 so that the bottom surface will be flush and will not cause scarring or 100 marring of a table, stand or shelf upon which the binder may be laid. These posts have rounded and tapered upper ends 18 and are formed with a plurality of grooves 19 for a purpose to be described. The sheets 13 have the holes 14 therein engaged upon 105 these posts and in this way all the sheets will be held against relative displacement. The posts are provided with grooves 16* within which engage screws 15* in the plates 110

15 for preventing the posts from slipping through the base when the holding means is released.

The binding means comprises a top or cover 20 which includes a stationary section 21 and a movable section 22 hinged upon one edge thereof in the same manner that the section 12 is hinged upon the section 11. The member 21 is partially or entirely hollow, and fitting therewithin is a frame 23 within which are pivoted, at 24, latches 25 which have their active ends engageable within the grooves 19 for holding the leaves 13 compressed. Extending through the hollow member 21 are bars 26 and 27 terminating in yokes 28 and 29, respectively, which straddle the latches 25 and which are pivotally connected therewith, as shown at 30. The inner ends of bars or rods 26 and 27 are threaded and connected by a turn-buckle 31 whereby the rods may be adjusted so that the latches 25 may be disengaged successively. Connected with the yoke 29 is a coil spring 32 which operates to hold the latches normally in engagement with the grooved posts.

For shifting the yokes to disengage the latches from the posts we provide a filler block 32^a which extends across the arms of the yoke 29 and with which is connected a plunger 33 slidable through a partition 34 in the member 21 and carrying a head or button 35.

In the use of the device the ledger sheets to be bound are engaged upon the posts and the top member is likewise slipped thereonto, the posts passing through the holes provided in the top member 21. As the top is pressed down the latches 25 will slide over the grooves in the posts until the sheets have been compressed fully or to the desired extent and the latches will remain engaged with the grooves and exert a pawl and ratchet-like action which will prevent the cover or top from moving upwardly. When, for any reason, it is desired to remove the top, as for instance when inserting more sheets or in removing the same, it is merely necessary that the operator grasp and pull upon the head or button 35 which will result in moving the yokes and rods longitudinally against the action of the spring 32 so that the latches will be withdrawn from engagement with the posts.

In carrying out the present invention, we provide a frame structure which includes a back 36, sides 37, an intermediate member 38, and upper and lower trays 39 and 40 respectively. The latter is intended to support the assembled binder which is placed thereon in upright position and so arranged that the posts 16 will be disposed above slots 41 in the tray or platform. At one end of the tray is a stop 43 which facilitates proper positioning of the binder. As the slots 41

are elongated, it is obvious that binders of different sizes may be accommodated, that is to say, the device will take care of binders in which the posts are different distances apart.

Extending longitudinally and mounted upon the top of the tray 39 near the back edge thereof, is an abutment cleat 44 against the forward side of which is disposed a longitudinal plate 45 of a squaring frame 75 which includes a rigid side plate 46 and a movable side 47 adjustable along the plate 45 and capable of being held in a desired position by means of clamping bolts 48 which pass through slots 49 in the plate 45. 80 This squaring frame is carried by strap hinges 50 mounted on the back 36 and the squaring frame is so arranged that it may be swung into the vertical position shown by dotted lines in Figure 1, with the plate 45 disposed in horizontal position upon the cleat 44. For maintaining this position, we provide a bracket 51 mounted on the back 36 and having its upper end 52 extended laterally and flush with the top surface of 90 the cleat.

Near one end, and in fact corresponding to the slots 41, the upper tray 39 is formed with a transverse groove 53 of a size and shape to receive the member 21 of the binder top or cover, and in the bottom of this groove are slots 54 adapted to receive the free ends of the posts 16 as will be explained. Mounted on one side 37 in vertical alignment with the slot 54 nearest the shelf 40 is a bracket 55 having a hole 56 and provided for a purpose to be explained.

In the operation, the assembled binder to be added to or to be corrected is laid upon the shelf 40 in engagement with the stop 43 and with the posts 16 above the slots 41. The operator presses slightly upon the top or cover of the binder and, at the same time, pulls upon the knob 35 to move the rods 26 and 27 lengthwise and swing the latches 25 out of engagement with the grooved posts whereupon the posts will drop gravitationally below the binder and into the slots 41, the screws preventing the posts from slipping through the base. The operator then removes the top or cover comprising the parts 21 and 22 and lays it in inverted position upon the tray 39 with the member 21 fitting within the groove 53, the post holes being above the slots 54. It should be understood that before doing this the squaring frame comprised by the parts 45 to 49 must be swung upon the hinges 50 into the vertical position shown by dotted lines in Figure 1. The top or cover 20 having been placed upon the shelf 39, the squaring frame is swung down so as to lie thereupon. The end member 47 must be adjusted with respect to the member 46, depending upon the size of the sheets to be 130

posted or bound. The sheets 13 are then removed from the previously assembled binder lying upon the tray 40 and are placed on the cover member 20 lying on the tray 39. Any new sheets to be added or inserted are treated in the same manner and it is apparent that the squaring frame will cause all the sheets to be disposed in registration so as to insure perfect alignment of the post receiving holes 14 provided therein. After all the sheets have been placed within the squaring frame, the frame is again swung into the vertical position, and the bottom member 10 of the binder is placed in position upon the top of the pile of leaves. The posts 16 which are still held within the base of the binder are then inserted through the registering holes and will be automatically latched by the members 25. By pressing down somewhat on the uppermost element, it is apparent that the leaves or sheets will be compressed and held firmly.

In order to line up statement and ledger sheets after posting, the statement sheets being shorter than the ledger sheets and being beneath the same when placed in the frame, the side member 46 of the frame is removed and a temporary post is inserted through the front hole of the binder after it is placed in position on the top tray 39, this temporary post passing through the forward slot 54 and engaging within the stop 55. After all the sheets have been posted, this temporary post is withdrawn and the sheets bound in the regular manner as above described.

From the foregoing description and a study of the drawings, it will be apparent that we have thus provided a simply constructed transfer tray device which will greatly facilitate the handling and binding of ledger or other sheets. The combination of this device with the peculiarly constructed binder provides an equipment which possesses multitudinous advantages, foremost among which is the elimination of the usual post to post transfer. Owing to the simplicity of the arrangement, it is obvious that very little skill will be involved in the operation of the binder so that the device should recommend itself to those having occasion to use the same.

While we have shown and described the preferred embodiment of the invention, it is to be understood that we reserve the right to make such changes in the form, construction and arrangement of parts as will not depart from the spirit of the invention or the scope of the subjoined claims.

60 We claim:-

1. A device of the character described comprising a frame carrying upper and lower trays arranged side by side, a squaring frame hingedly mounted upon the upper tray, the upper tray being formed with slots

adapted to receive binding posts of a loose-leaf binder and the lower tray being formed with corresponding slots and adapted to support a binder having releasable slidable posts, the slots in the lower tray being adapted to permit the dropping down of the posts subsequent to their release from the binder.

2. A device of the character described comprising a frame carrying upper and lower trays arranged side by side, a squaring frame hingedly mounted upon the upper tray, the upper tray being formed with slots adapted to receive binding posts of a loose-leaf binder, and the lower tray being formed with corresponding slots and adapted to support a binder having releasable slidable posts, the slots in the lower tray being adapted to permit the dropping down of the posts subsequent to their release from the binder, said squaring frame having one end rigid and its other end adjustable whereby to accommodate ledger leaves of different sizes.

3. A device of the character described comprising a frame carrying upper and lower trays arranged side by side, a squaring frame hingedly mounted upon the upper tray, the upper tray being formed with slots adapted to receive binding posts of a loose-leaf binder, and the lower tray being formed with corresponding slots and adapted to support a binder having slidably mounted posts, the slots in the lower tray being adapted to permit the dropping down of the posts subsequent to their release from the binder, and a stop bracket on the frame beneath the first named slot nearest the lower tray and adapted to support a temporary post.

4. A transfer device for use in connection with a loose-leaf binder having bottom and top members and equipped with releasable slidably mounted posts held in place by releasable catch means, comprising upper and lower trays, the lower tray being adapted to support the binder and formed with slots through which the posts thereof may drop partially, when said catch means is released, the upper tray being adapted to support the top member of the binder in inverted position and formed with slots adapted to register with the post receiving holes of said top member, and an adjustable squaring frame hinged upon the upper tray and adapted to seat upon said upper member of the ledger thereon to register ledger leaves placed therein.

5. A transfer device for use in connection with a loose-leaf binder having bottom and top members and equipped with slidably mounted posts held in place by releasable catch means, comprising upper and lower trays, the lower tray being adapted to support the binder and formed with slots through which the posts thereof may drop

partially when said catch means is released, seat upon said upper member of the ledger the upper tray being adapted to support the thereon to register ledger leaves placed top member of the binder in inverted position.

10
5 tion and formed with slots adapted to register with the post receiving holes of said top member, an adjustable squaring frame hinged upon the upper tray and adapted to

In testimony whereof we hereunto affix our signatures.

EDMUND A. SCHWARTING.
AUGUST R. SCHRADE.
